US00D534543S

(12) **United States Design Patent** (10) **Patent No.:** **US D534,543 S**
(45) **Date of Patent:** **** Jan. 2, 2007**

- (54) **ICON FOR A PORTION OF A DISPLAY SCREEN**
- (75) Inventors: **Paul Gusmorino**, Seattle, WA (US); **Mark R. Ligameri**, Austin, TX (US); **Jenny T. Lam**, Seattle, WA (US); **Greg S. Melander**, Redmond, WA (US)
- (73) Assignee: **Microsoft Corporation**, Redmond, WA (US)
- (**) Term: **14 Years**
- (21) Appl. No.: **29/228,395**
- (22) Filed: **Apr. 22, 2005**
- (51) **LOC (8) Cl.** 14-04
- (52) **U.S. Cl.** **D14/492**
- (58) **Field of Classification Search** ..... D14/485-95, D14/371, 374, 388, 125-29, 341-46, 450; D18/32, 33; D19/6, 1; D20/11; D21/324, D21/329; 715/700-866, 976, 978; 235/379-80; 455/24; 250/208.1; 463/1; 341/22; D13/162; 273/157 R, 282.1; 236/94, 1 C; 345/757, 345/782, 848, 852, 850, 809, 837, 798, 752, 345/163, 156, 168, 169, 537, 474, 836, 419, 345/649, 656, 659, 426, 427, 582, 428, 440, 345/660, 634, 902, 418, 629, 175-178, 181, 345/173, 174

(57) **CLAIM**

The ornamental design for an icon for a portion of a display screen, as shown and described.

DESCRIPTION

The FIGURE is a front view of an icon for a portion of a display screen showing our new design. The broken line showing of the display screen is for illustrative purposes only and forms no part of the claimed design.

1 Claim, 1 Drawing Sheet
